CLAIM

The ornamental design for an organizer tray for as-
sorted desk accessories, as shown and described.

DESCRIPTION

FIG. 1 is a top plan view of an organizer tray for as-
sorted desk accessories showing my new design;

FIG. 2 is a bottom plan view thereof;

FIG. 3 is a front elevational view thereof;

FIG. 4 is a rear elevational view thereof;

FIG. 5 is an elevational view of one side of the desk

tray, the other side view being identical thereto; and,

FIG. 6 is a front, upper right perspective view thereof.
